UNITED STATES PATENT OFFICE.

GEORGE STOWE, OF NEW YORK, N. Y., AND GEORGE E. MOLYNEUX, OF BAYONNE, NEW JERSEY, ASSIGNEES OF ONE-THIRD TO R. M. OWEN.

COMBINATION LAMP AND HORN.

1,271,097.

Specification of Letters Patent Patented July 2, 1918.

Application filed August 22, 1916. Serial No. 116,274.

To all whom it may concern:

Be it known that we, GEORGE STOWE and GEORGE E. MOLYNEUX, both citizens of the United States, residing, respectively, in the 5 borough of Manhattan, city, county, and State of New York, and Bayonne, county of Hudson, and State of New Jersey, have invented certain new and useful Improvements in Combination Lamps and Horns, of which the following is a specification.

This invention relates to automobile accessories and particularly to a combination lamp and horn.

Among the objects of our invention may be noted the following: to provide a simple, compact, combination structure which is cheap to produce and which is effective both for lighting and sound producing purposes; to provide a structure wherein simple means 20 are employed to combine a modern automobile lamp with an audible signaling device, such as is usually carried by said vehicle; to combine, in a single structure, a plurality of signals, such as are required by traffic regulations, which are effectively disposed and give the highest possible efficiency; to provide a compact structure by which an electric horn or signaling device and an electric light or lights may be intimately associated, 25 and the former hidden by the latter, and to provide means by which such different signaling devices may be combined in a single structure for use on automobiles, or other road vehicles, without destroying the utility and operation of either device, the association of these important devices being 30 in an exceedingly limited space, and the disposition being such as to eliminate liability to injury and to economize space and 40 trappings on the car.

With the above objects in view and others which will be detailed during the course of this description, our invention consists in the parts, features, elements and combinations thereof, hereinafter described and 45 claimed.

In order that our invention may be clearly understood, drawings have been provided wherein:

50 Figure 1 is a sectional elevation of a modern automobile lamp, having our invention embodied therein;

Fig. 2 is an elevation, showing the position of the sound passage of the lamp relatively to the supporting post thereof; and

Fig. 3 is a sectional elevation showing a detail of our construction as embodied in the lamp.

Referring to the drawings, the numeral 1, indicates a portion of the supporting post 60 or upstanding bracket employed on many makes of automobiles, the upper end of said post being usually screw-threaded for the reception of a nut or other securing means, producing the joint between said post and 65 a tubular member 2, forming part of or attached to the frame member 3, of a conventional form of lamp. The lamp at its front is provided with a lens 4, held in the bezel 5, secured to the front of the frame in any 70 suitable manner. The usual reflector 6, is supported at its front by the bezel 5, and supports at its rear end the socket 7, holding an incandescent bulb 8, and to which is attached the usual plug 9, to which the 75 leads 10, from a battery, generator or other source of electrical energy, are attached, said leads passing through the tubular member 2 and its support, as usual. Near the rear of the lamp frame 3, and preferably 80 below the horizontal diameter of the lamp, an aperture 11, is formed in the lamp frame 3, formed by striking up the metal of said frame to produce the flange 12, Fig. 1. This aperture is preferably slanted both 85 downwardly and rearwardly relatively to the horizontal diameter of the lamp frame, thus preventing rain from beating into the interior of the lamp, or water running into the interior of the lamp when the car is being washed. Preferably, to give a nice finish and also to provide a supporting means for the body of the audible signaling device, a ferrule 13, is set within the aperture with 90 a flange 14, turned over the lamp frame 3, about said aperture. Integral with, or otherwise connected to, the said ferrule is the body 15, or supporting member of the signaling device, within the flange 16, of which the mechanism of the device is set and supported. The details of the audible signaling device, as shown in Fig. 1, are conventional and intended to be only diagrammatically shown; but, sufficient of said device, which is preferably an electrically operated 105 horn, of the vibratory type, is shown in Fig. 1, to enable one skilled in the art to appreciate its structure and disposition within the lamp body. The leads 17, of the signaling device, extend through the tubular member 110

2 and its supporting post to the source of power for operating the same, and the disposition of the sound producing diaphragm 18, is such as to enable the full volume of 5 sound to flow through the aperture 11.

Viewing Fig. 3 it will be seen that the ferrule body 15, at opposite portions of its circumference, rests, as at 19, upon the lamp frame 3, by which means the signaling 10 device is quite firmly supported within the lamp, and thus prevented from shaking loose, rattling and weakening the connection of said device within the lamp frame. It will also be noted, viewing Fig. 1, that the 15 signaling device is located between the lamp frame 3, and the reflector 6, being thus disposed without increasing the size of the lamp beyond what is required and essential for the introduction of the bulb-attachments 20 of the visible signaling device, which latter is of the type now commonly employed to which different voltages are conveyed for the purpose of giving more or less of candle power to the light.

25 From the foregoing description, it will be understood that the lamp occupies its usual place and is not interfered with either as to efficiency or display in any manner, while the audible signaling device is so disposed 30 as to be thoroughly effective, give a large volume of sound and not be interfered with in any manner by the visible signaling device, or any of its parts. The volume of sound is very great, owing to the comparatively small aperture 11, and the finite space 35 in rear thereof, which causes the diaphragm to operate both as a producer and a reflector or projector of sound. It will also be seen that the space between the reflector 6 and 40 frame 3 is closed at the front by the bezel 5, so that the horn or audible signaling device is completely concealed and is so disposed, as to avoid any injury to it unless the lamp is severally crushed or broken. Sound 45 from the audible signal, therefore, is emitted from the single opening or aperture 11. Against ordinary accidents, blows, etc., the

horn is thoroughly protected by its disposition in the casing; and the location of the horn on the car is such as to make it exceedingly effective, and enable its full blast to be heard at a great distance. 50

We are not to be limited to details of construction, nor to the particular type of signaling devices shown, the latter being 55 merely illustrative or suggestive.

Having thoroughly described our invention, what we claim and desire to secure by Letters Patent is:

1. A lamp casing having a reflector set 60 therein with a space between the two, the reflector being held suspended in the casing by a connecting bezel which entirely closes the front of the casing; said casing having an aperture therethrough near its back; a 65 ferrule or casing set in said aperture; a signaling device mounted on said ferrule, and having its sound-producing members arranged over the opening at the inner end of said ferrule, substantially as described. 70

2. A lamp having its casing provided with an aperture near the rear thereof; means for supporting the lamp in a predetermined position in said casing so as to entirely close the front of said casing; the said aperture 75 being directed through the casing downwardly and backwardly relatively to the horizontal diameter of the casing; and a signaling device mounted in the casing with its sound-producing element directly over 80 the aperture, substantially as described.

3. A lamp having its casing entirely closed at the front and provided with an aperture near its rear; and an electric signaling device mounted within the casing 85 with its sound-producing members directly over and closing one end of said aperture, the frame of the signaling device and said casing being in engagement at several points so as to firmly support said device and prevent it from jarring loose or rattling. 90

GEORGE STOWE.
GEORGE E. MOLYNEUX.
